AUTOMATICALLY ADJUSTABLE POWER
SUPPLY FOR X-RAY TUBES

William J. Phelan, Olyphant, and James B. MacPherson,
Clarks Summit, Pa., assignors to Weston Instruments,
Inc., a corporation of Texas

Filed Oct. 22, 1962, Ser. No. 232,076
4 Claims. (Cl. 250—103)

The present invention relates to an accurately controlled adjustable power supply for an X-ray tube and has for an object the provision of a system of compensation for undesirable variations in X-ray tube beam intensity which occur when the supply level setting is changed.

Adjustable high voltage power supplies for X-ray tubes have heretofore been used to set the intensity of the X-ray beam at differing desired levels. However, a disadvantage in these systems is that the beam intensity will not vary directly with change in setting of the supply potential as a result of static charge which has been built up on the walls of the X-ray tube. For example, upon change from a higher level setting to a new lower level setting the excess of the static charge between the two levels produces, before it has leaked off, values of tube resistance, tube potential and tube current different from their steady state values ordinarily produced at the new setting. As the excess charge leaks off, the foregoing values will change and thus the beam intensity will vary until the new steady state values have been reached. This variation in beam intensity for each new setting is very undesirable when there is required rapid change between settings along with a high degree of accuracy.

Accordingly, an object of the present invention is to rapidly compensate for undesirable variations in X-ray beam intensity resulting from the leaking off of excess static charge which has been built up in the tube.

Another object of the invention is to compensate for undesirable variations in intensity with the compensation being a function of the variation of the average tube current.

In a preferred form of the invention there is connected in circuit with the X-ray tube, means for producing a compensation signal which varies as a function of the current flow through the X-ray tube. In response to the magnitude of this compensation signal, the high voltage applied to the X-ray tube is adjusted to compensate for the undesirable variations in beam intensity.

In carrying out the invention in one form thereof a source of supply is connected by way of a high voltage step-up transformer to the X-ray tube. A control circuit is connected to the source for comparing the output thereof with a selected reference potential level. As a result of this comparison, there is produced a feedback to the source to control the magnitude of the high voltage applied to the X-ray tube. In accordance with the present invention the compensation signal which varies as a function of the tube current is applied to the control circuit for further changing the feedback. As a result, the magnitude of the high voltage applied to the X-ray tube is varied as a function of the changing tube current to provide the compensation for the undesirable variations in beam intensity. In this manner, and in accordance with the above example, upon change from a high to a lower level setting of supply potential, the X-ray tube beam intensity is constantly and accurately maintained at its desired new steady state value.

2

Further, in accordance with the invention, the direction of compensation for variation in beam intensity is dependent on the effective resistance of the X-ray tube with respect to the effective source resistance of the power supply. Thus, for example, upon change to a new lower level setting of the supply, the tube resistance and the tube potential are at a higher value and the tube current is at a lower value than their new steady state values. Since the resultant beam intensity is proportional to the square of the tube potential times its current, if the tube resistance is less than two times the source resistance, the intensity will have been increased beyond its steady state value. To compensate for that increase, the tube potential is decreased accordingly. On the other hand, if the tube resistance is greater than two times the source resistance, the resultant intensity will have been decreased beyond its steady state value. To compensate for that decrease, the tube potential is increased accordingly.

For further objects and advantages of the invention and for a description of its operation, reference is to be had to the following detailed description taken in conjunction with the accompanying drawings in which:

FIG. 1 schematically illustrates an adjustable power supply for an X-ray tube according to the invention with the X-ray tube resistance being less than two times the source resistance; and

FIG. 2 schematically illustrates a further embodiment of the invention with the X-ray tube resistance being more than two times the source resistance.

Referring now to FIG. 1, the adjustable power supply for the X-ray tube 10 has been illustrated as including a high voltage step-up transformer 11 having the tube 10 connected to its secondary windings 11b and 11c. The primary winding 11a of transformer 11 is connected to a source of supply including a transformer 13, a diode 15, and a control circuit 16. A regulated source 14 applies an alternating current voltage to the primary winding 13a of the step-up transformer 13 to produce at the secondary winding 13b a regulated alternating current voltage. This voltage is rectified by the diode 15 so that only the positive-going half cycles are applied therethrough and to the plates 20a and 20b of tube 20. The cathodes 20c and 20d of tube 20 are connected by way of resistors 21 and 22, respectively, to a common junction and then by way of ground to the lower end of primary winding 11a, the upper end of which is connected by way of conductor 18 to the upper end of winding 13b.

Tube 20 of control circuit 16 is maintained normally conductively biased so that upon application thereto of a positive-going half cycle current flow may be traced from winding 13b, through diode 15, tube 20, to ground, and through winding 11a, conductor 18 to winding 13b. In this manner, there is provided a low impedance path between the secondary winding 13b of the source transformer 13 and the primary winding 11a of the high-voltage transformer 11 which is effective to produce a high voltage across its secondary windings 11b and 11c.

In the secondary circuit of transformer 11 the upper end of winding 11b is connected to the anode of tube 10, one terminal of the filament of which is connected to the lower end of winding 11c. The upper end of winding 11c is connected by way of resistor 12 to ground. Thus, current flows from winding 11b, through the X-ray tube 10, winding 11c and then by way of resistor 12 to ground. The resultant potential drop across resistor 12 is positive with respect to ground and is proportional to the

peak values of the X-ray tube current. It will later be described how that potential drop is effective to provide the compensating action in accordance with the present invention.

When tube 20 is non-conductively biased, the supply circuit for primary winding 11a during the positive half cycles may be traced from winding 13b by way of diode 15, resistor 23, ground, winding 11a, conductor 18 and then to the winding 13b. Since the resistor 22 is selected to have a substantially large value, the potential that is then produced across primary winding 11a is negligible compared with its value when tube 20 is conductive. Thus, the biasing of the tube 20 controls the amount of the half cycle that is effectively applied to the winding 11a and in this manner increases or decreases the energizing high voltage applied to the X-ray tube.

The controlled half cycle appearing at the upper end of winding 11a is of a negative-going potential and that upper end is connected by way of conductors 18 and 23, diode 24, winding 26a, contact 28a and potentiometer 28 to ground. The upper end of potentiometer 28 is connected to a source of negative reference potential, as for example battery 30, and the setting of the slider 28a on the resistor 28 determines the potential at the slider with respect to ground. Thus, the diode 24 is not rendered conductive until the leading edge of the negative half cycle has reached a magnitude of greater value in a negative direction than the negative potential applied to the slider 28a. At the time diode 24 is rendered conductive a signal is produced across the primary 26a of the transformer 26 which results in an output across its secondary 26b.

As previously described, X-ray tube current flow through resistor 12 is effective to produce at the upper end thereof, a potential drop positive with respect to ground. This potential drop has the effect of reverse biasing diode 31 which reverse bias must be overcome by a negative potential produced at the upper end of winding 26b with respect to ground before diode 31 will become conductive. When that negative potential is sufficient to render diode 31 conductive, current flow in the secondary circuit of transformer 26 may be traced from ground through resistor 33, conductive diode 31, winding 26b, resistor 12 to ground. In this manner with diode 31 conductive, an input signal is applied to the amplifier 32.

It will now be understood that the effect of the reverse bias positive potential produced across resistor 12 is to increase the amount by which the output signal across winding 26b must exceed the level of the bias before diode 31 is rendered conductive and an input signal is applied to amplifier 32. It is in this manner that the desired compensating action is produced by the proper selection of the resistance value of resistor 12. The amplifier 32 is of the conventional resistance capacitance coupled type and thus amplifies and inverts the input signal which is then applied by way of conductor 34 to the input of a one-shot or monostable multivibrator 37.

One-shot multivibrators are well known in the art and are described in detail in Pulse and Digital Circuits, by Millman and Taub, McGraw-Hill, 1956, at page 174 et. seq. As set forth in this text a one-shot multivibrator is induced to make a transition from its stable state to its quasi-stable state by the application of an input signal or pulse. After such transition, the multivibrator 37 will remain in its quasi-stable state for a desired period of time by proper selection of circuit element values and connections as described in detail in the foregoing text. In the present invention, the multivibrator 37 has a quasi-stable state time duration at least equal in time to one-half cycle of the frequency of the regulated source 14 to provide proper timing of the nonconductive bias to tube 20, as will later be explained in detail. The output of the multivibrator 37 provides a positive-going pulse of rectangular wave shape during the time of the stable state and upon transition to its quasi-stable state there is produced a negative-going pulse of rectangular wave shape.

The output of the multivibrator 37 is applied to D.C. restorer 39 comprising a capacitor 39a, a triode 39b, and a resistor 39c. Accordingly, the output of the multivibrator 37 is connected by way of capacitor 39a to the common connection of the plate and grid of tube 39b and the resistor 39c, the other end of which resistor is connected to ground. D.C. restorers of similar type are described in detail at page 119 et. seq. of the above-named text where it is shown that the top or positive extremity of the positive-going pulses are restored or clamped to ground. Thus, during the time of the stable state the positive-going output pulse from multivibrator 37 is clamped to ground potential which is applied by way of conductor 42 and resistors 43 and 44 to the respective grids 20e and 20f of the tube 20. Accordingly, the resultant potential applied to the grids 20e and 20f with respect to the cathodes 20c and 20d is effective to maintain conductive tube 20 during the time of the stable state of the multivibrator 37.

Upon application of a switching pulse to the multivibrator 37, the output negative-going pulse of rectangular wave shape achieves, by means of the restorer 39, a negative potential with respect to ground. This negative potential is applied as a feedback signal by way of conductor 42 and resistors 43 and 44 to nonconductively-bias tube 20, thus effectively to cause current not to flow through the winding 11a. Since the time duration of the quasi-stable state and thus the time duration of the negative pulse is at least one half cycle, the tube 20 is maintained nonconductive at least until the termination of the negative half cycle produced across winding 13b.

It will now be understood that the resultant wave shape of the signal produced across the winding 11a will be the wave shape of the leading edge of the half cycle with the wave shape returning to ground potential at the time tube 20 is rendered nonconductive. By adjusting the setting of slider 28a, the time is changed during the leading edge when tube 20 is rendered nonconductive and thus, to change the resultant magnitude of the pulse developed across winding 11a.

It will be assumed in this embodiment of the invention, that the resistance of the tube 10 is less than two times the effective resistance of the source which may be considered to be the resistance looking back into the supply circuit from the tube 10. Accordingly, as previously described, upon change to a new lower level setting, the beam intensity increases beyond the value it would ordinarily have at that new setting. In order to provide compensation for that increase, the high voltage supply potential applied to the tube 10 must be decreased accordingly.

Thus, in operation of the adjustable power supply of FIG. 1, the slider 28a may be moved in a downward direction to decrease the reference potential applied thereto when it is desired to decrease the beam intensity setting to a new lower value. As a result of the excess static charge, the tube current decreases to a value lower than the steady state value it would have ordinarily at the new setting of the slider 28a. As a result of this decreased current flow, the potential drop across resistor 12 is decreased in proportion to the peak tube current so that the reverse bias on the diode 31 is also lower than its steady state value at that new setting. Thus, a lower value of negative potential is allowed to pass through diode 31 which is amplified by amplifier 32 to trigger multivibrator 37 to its quasi-stable state at a point in time before it would ordinarily be triggered. In this manner the tube 20 is rendered nonconductive at an earlier time on the leading edge of the half cycle thus to produce a pulse across the winding 11a of magnitude less than the value it would ordinarily have at the new setting. In this manner, the high voltage supply potential for the tube 10 is decreased as a function of the changing peak tube current to provide the compensating action for the increased beam intensity. That decrease in potential will exactly

balance out the increase in intensity by proper selection of the resistance value of resistor 12.

As the excess static charge leaks off from the walls of the X-ray tube 10, the tube current will approach its steady state value which will be accurately and rapidly followed by the compensating action to provide at the new setting a constant value of beam intensity.

Referring now to FIG. 2, it will be seen that many of the parts of the adjustable power supply for the X-ray tube 10 are identical with those of FIG. 1 and, therefore, have been identified by corresponding reference characters. However, it will be noted that the upper end of winding 11c is connected by way of a parallel combination of resistor 12a and capacitor 47 to ground. The upper end of the parallel circuit is connected by way of resistor 46 and capacitor 49 to ground. Accordingly, resistors 12a and 46 and capacitors 47 and 49 comprise a filter circuit to provide a potential across the capacitor 49 which is proportional to the average D.C. component level of the pulse signal applied from the winding 11c. The time constant for this filter circuit is selected to be long with respect to the frequency of the supply 14, but very short with respect to the incremental changes of the setting of the slider 28a.

The upper end of capacitor 49 is connected to ground by way of a voltage divider comprising resistors 48 and 12b. Resistor 12b is shunted by capacitor 51 which is effective to absorb the pulse from winding 26b without loss in amplitude of the pulse. The common connection of the resistors 48 and 12b is coupled by way of resistor 33, diode 31, secondary winding 26b, and battery 45 to ground. The battery 45 is connected to reverse bias diode 31 while the potential drop produced across resistor 12b is effective to produce a forward bias for that diode. Accordingly, the values of the foregoing components are selected so that during the time the transformer 26 is not energized, the diode 31 is nonconductive. When that transformer is energized and a negative-going signal is produced across winding 26b of sufficient magnitude, diode 31 is rendered conductive thereby to provide a signal input to the amplifier 32.

In the embodiment of FIG. 2 it will be assumed that the resistance of X-ray tube 10 is greater than two times the effective resistance of the power supply source. Accordingly, as previously described, upon change to a new lower level setting of the slider 28a, the tube current and the beam intensity will have been decreased below the values that they would ordinarily have at the new setting. In order to provide compensation for the decrease in intensity, the supply potential applied to the tube 10 must be increased in the manner now to be described.

Upon change to the new lower level setting of the slider 28a, the tube current decreases and the potential drop across resistor 12a, as well as the potential across capacitor 49, also decreases. As a result of the voltage divider action of resistors 48 and 12b, the potential at the common junction thereof is decreased as a proportion of the potential across capacitor 49 which is applied by way of resistor 33 to the anode of diode 31 to decrease its forward bias to a value lower than its steady state value at the new setting.

With the forward bias decreased, a higher value of negative-going signal is required to be produced across the secondary winding 26b in order to render diode 31 conductive thereby to provide a signal input to the amplifier 32. This higher valued negative-going signal is provided at a later time on the leading edge of the half cycle at which time the multivibrator 36 will be triggered to render tube 20 nonconductive. Thus, a greater portion of the leading edge of the sine wave is applied across winding 11a which provides an effective pulse of magnitude greater than the value it would ordinarily have at the new setting. It is in this manner that the high voltage supply potential for the X-ray tube 10 is increased to provide the compensation for the decreased beam intensity

when the tube resistance is greater than two times the source resistance.

It will now be understood that the filter which comprises resistors 12a and 46, and capacitors 47 and 49 is effective to provide compensation as a function of the variation of the average tube current rather than as a function of the peak tube current as provided in the system of FIG. 1.

Now that the principles of the invention have been explained, it will be understood that many modifications may be made. For example, the filter of FIG. 2 may be utilized with the system of FIG. 1 to provide compensation as a function of the variation of the average tube current when, as assumed in FIG. 1, the tube resistance is smaller than two times the source resistance.

What is claimed is:

1. An adjustable power supply for an X-ray tube having compensation for undesirable variations in the intensity of the X-ray beam resulting from the leaking off of excess static charge built up in said tube when the applied high voltage is decreased to a lower voltage comprising, a high voltage source of supply, a high voltage transformer having its primary winding connected to said source of supply and its secondary winding connected to said tube, reference means for selectively producing reference potentials, means connected to said source of supply and to said reference means for comparing the output of said source with a selected reference potential to produce a feedback signal, means including a switching device coupled to said source of supply and to said primary winding and responsive to said feedback signal for controlling the magnitude of the voltage applied to said tube, means connected in circuit with said tube for producing a potential change proportional to the change in the current flow through said tube, and means responsive to the magnitude of said potential change for producing a corresponding change in said feedback signal thereby to further change the magnitude of said voltage applied to said tube as a function of the change in said tube current and to compensate for said variations in beam intensity resulting from the leaking off of said excess static charge.

2. An adjustable power supply for an X-ray tube having compensation for undesirable changes in beam intensity which occur when the applied high voltage is decreased to a lower voltage comprising,

a high voltage source of supply, a high voltage transformer having its secondary winding connected to said tube and its primary winding connected to said source of supply, switching means connected in circuit with said source of supply and said primary winding and operable for changing the magnitude of the potential produced across said primary winding, reference means for selectively producing reference potentials, control means connected to said primary winding and to said reference means for comparing the magnitudes of the signals produced therefrom and to provide a feedback signal to said switching means, impedance means connected in circuit with said tube for producing a compensation signal proportional to the change in the current flow through said tube, and means responsive to the magnitude of said compensation signal and connected to said control means for varying said feedback signal thereby changing said potential across said primary winding whereby the high voltage for the X-ray tube is varied as a function of the tube current to produce compensation for said variations in beam intensity.

3. The adjustable power supply of claim 2 in which said responsive means includes at least one diode having an anode and a cathode and in which there is provided means connecting said cathode to said impedance means for producing a reverse bias for said diode which varies as a function of said compensation signal. 5

4. The adjustable power supply of claim 2 in which said responsive means includes at least one diode having an anode and a cathode and in which there is provided means connecting said anode to said impedance means 10 for producing a forward bias for said diode which varies as a function of said compensation signal.
